UNITED STATES PATENT OFFICE.

MARSHALL J. WYERS, OF PHOENIX, ARIZONA.

CONCRETE-PIPE JOINT.

1,241,323.

Specification of Letters Patent. Patented Sept. 25, 1917.

Application filed April 21, 1917. Serial No. 163,662.

To all whom it may concern:

Be it known that I, MARSHALL J. WYERS, residing at Phoenix, in the county of Maricopa, State of Arizona, a citizen of the United States, have invented certain new and useful Improvements in Concrete-Pipe Joints; and I do hereby declare the following to be a full, clear, and exact description of the invention, such as will enable others skilled in the art to which it pertains to make and use the same.

My invention relates to an improvement in concrete pipe joints especially designed for use with concrete, terra cotta and other drain or service pipes of a similar nature.

The object of the invention is to provide a joint for a concrete pipe to be used for draining waste water and for conveying water for irrigating and other numerous purposes.

A further object is to provide a joint for a concrete pipe arranged and formed in such a manner that the pipe will be watertight.

A further object is to provide a pipe with a joint which is simple, inexpensive and durable in construction, not liable to get out of order and which attains the desired result in a perfect manner.

The invention consists in the several features and in the construction, combination and arrangement of features as more fully hereinafter described and claimed.

Referring to the drawings:—

Fig. 1 is a side view in elevation.

Fig. 2 is an end view.

Fig. 3 is a central longitudinal section.

Fig. 4 is a side view in elevation of one of the inner joint sections.

Fig. 5 is a side view in elevation of my invention when in use as a flume.

Fig. 6 is a cross-section on the line $\alpha-\alpha$ of Fig. 5.

Fig. 7 is a longitudinal sectional view of a modified form of joint.

In the drawings in which similar reference characters denote similar parts throughout the several views, 1 represents a line of concrete drain pipe comprising a plurality of annular hollow inner sections 2 placed or laid end to end and which taper or incline inwardly as at 3 from a point 4, at substantially the middle thereof, to each end 5.

Breaking joint with the inner sections 2 are a plurality of annular outer sections 6 placed or laid end to end over the annular

inner sections 2 the inner surfaces of which are tapered outwardly as at 7 from a point 8, at substantially the middle thereof, to each end 9.

The outer annular sections 6 are usually or preferably made 12 inches in length and 5 inches in diameter on the outside, 3 inches inside diameter at middle point 8 and $\frac{1}{4}$ inches at each end, while the inner annular sections 2 are made 12 inches long with two inch waterway or channel, 4 inches in diameter at the middle point 4 and 3 inches at each end.

It will be seen that a line of pipe constructed or formed of sections made in accordance with my invention will be exceedingly easy to assemble and the size and weight of the sections render them easy to handle both in loading and unloading and in laying or placing them when forming the line of pipe.

In the modified form of my invention shown in Fig. 7 of the drawings a plurality of annular inner hollow sections 10 are provided each having an exterior surface 11, curved outwardly from end to end, and breaking joint with a plurality of annular outer hollow sections 12, the inner diameter of the sections 12 curving or flaring outwardly as at 13 from a point 14, at substantially the center, to each end 15 thereof.

I do not wish to be understood as limiting myself to the specific details of construction and arrangement as herein-described and illustrated, as it is manifest that variations and modifications may be made in the features of construction and arrangement, in the adaptation of the device to various conditions of use, without departing from the spirit and scope of my invention and improvements. I therefore reserve the right to all such variations and modifications as properly fall within the scope of my invention and the terms of the following claims.

What I claim is:—

1. In a built up pipe, the combination of a plurality of inner hollow sections each having an enlarged middle portion and an outer surface tapering from said enlarged middle portion to each end, a plurality of outer hollow sections each having an enlarged middle portion and adapted to fit over the inner sections and the inner surface of each tapering from said enlarged portion to each end, the enlarged middle portions of the inner sections reinforcing the

connection between the end portions of the outer sections and the enlarged middle portions of the outer sections reinforcing the connection between the end portions of the 5 inner sections thereby forming a pipe of uniform diameter throughout.

2. In a built up pipe, the combination of a plurality of inner hollow sections the ends of which are contracted and abut against 10 each other and the middle portions of which are enlarged, a plurality of outer hollow sections the middle portions of which are enlarged and the ends of which abut against

each other, the connection between said ends being reinforced by the said enlarged portions of the inner sections, and the inner surfaces of the outer sections fitting the contour of the outer surfaces of the inner sections and the connection between the ends of the inner sections being reinforced by the 20 enlarged portions of the outer sections thereby forming a pipe of uniform diameter throughout.

In testimony whereof I have affixed my signature.

MARSHALL J. WYERS.
